UNITED STATES PATENT OFFICE

EDWIN A. PETERSON, OF ST. PAUL, MINNESOTA, ASSIGNOR TO EDISON ELECTRIC APPLIANCE COMPANY, INC., OF CHICAGO, ILLINOIS, A CORPORATION OF NEW YORK

FLATIRON

Application filed March 12, 1929. Serial No. 346,425.

My invention relates to flatirons and has for its object the provision of an improved flatiron whereby the fabric under and around the buttons or the like of a garment may be 5 pressed in a convenient and efficient manner.

Certain irons, heretofore, have been provided for pressing the cloth under and adjacent the buttons of a garment. Generally these irons were provided with recesses or 10 grooves in the ironing surface for receiving the buttons in the ironing operation. Irons of this character were more or less objectionable in that it proved very difficult because of the recess to slide the iron sidewise or to rotate the iron as is usually desired in ordinary 15 ironing operations. Moreover, the recesses often collected dirt and their edges often rusted.

My invention contemplates the provision 20 of a flatiron whereby the fabric under and around buttons may be pressed without sacrificing the advantages derived from a smooth and uninterrupted ironing surface.

In carrying my invention into effect in 25 one form thereof, I provide a recess or slot in the side of the iron above the ironing surface. As the iron is moved over the garment or fabric being pressed, the recess will receive the button laterally so that the cloth 30 under and around the button will be pressed without danger of tearing the button from the garment and without damage to the button itself. To accommodate the iron to both right and left handed persons, and to 35 facilitate pressing operations in general, each side of the iron may be provided with a recess.

For a more complete understanding of my 40 invention reference should be had to the accompanying drawing in which Fig. 1 is a perspective view of an electric flatiron embodying my invention; Fig. 2 is a fragmental view in section illustrating the recesses provided in both sides of the iron; and Fig. 3 is 45 a section of the iron taken through the line 3 of Fig. 2.

Referring to the drawing, I have shown my 50 invention in one form in connection with an electric flatiron. As shown, the iron is provided with a heavy ironing body shown as a

sole plate 10, a suitable cover member 11 and an ordinary grip or handle 12. These members will be secured in any suitable manner as for instance by screw fastening means 13. It will be understood that the flatiron will be 55 provided with a suitable heating element (not shown), the terminals of which will be brought to a conventional plug socket 14 so as to provide for external electrical connection with a suitable electrical supply source. 60

In order that the material under and about the button of a garment or the like may be pressed in a convenient and efficient manner, I provide each side of the ironing body 10 with a groove or recess 15. Preferably, 65 these recesses will be located toward the point, i. e., in the forward portion of the iron. It will be understood that each recess will be positioned adjacent the working surface of the iron so as to receive the button 70 laterally in the ironing operation and thereby permit the edge of the ironing surface 16 beneath the recess to press the cloth under the button, as shown in Fig. 3. Obviously, each recess may take any suitable shape and 75 have any suitable dimensions, the particular size and shape of the buttons to be received being determining factors. As shown, the lower wall 15a of the recess is inclined downward toward the side of the iron. Preferably, the ends of each recess will be tapered 80 as indicated 15b, 15c, so that the button will slide freely into and from the recess as the iron is moved forward without injury to either the button or its fastening means. It 85 will be observed that since the recess is located adjacent the pressing surface 16 of the iron, but a very thin portion 17 of the side wall is left between the recess and the pressing surface. Obviously, this construction facilitates the reception of the button by the recess. Although it is not essential to 90 my invention, the side or edge surfaces of the sole plate 10, within which the recesses are formed, should be substantially vertical. This construction serves both to facilitate the ironing operation and to provide the maximum weight commensurate with the working area of the iron.

It will be understood in the ironing oper- 100

ation, that one or the other of the recesses 15 will serve to receive the button laterally as the iron is passed over the adjacent material (Fig. 3). Thus, the iron may be guided so that the edge of its pressing surface 16 beneath the recess will pass beneath the adjacent half of the button and thereby press the fabric thereunder. Likewise, the fabric under the other half of the button may be pressed. It will be understood that the material under the button may be pressed, if desired, by rotating the iron about the button, the button, of course, being received in the recess during this operation.

15 By providing two recesses 15, one for each side of the iron, I accommodate the iron readily to both right and left handed persons. Moreover, the two recesses facilitate the ironing operation even though the operator uses 20 but one hand only. Thus, the operator may iron under both sides of the button by nosing the iron forward, first on one side of the button and then on its other side.

It will be observed that I have provided an 25 iron so that the material under a button or the like may be conveniently pressed without danger of tearing the button from the fabric or of damaging the button itself. Moreover, the material adjacent the button 30 may be pressed more efficiently since there is no danger because of the recess of injuring the button or of tearing it from the fabric.

While I have, in accordance with the provisions of the patent statutes, described my 35 invention as embodied in concrete form and operating in a specific manner, it should be understood that I do not limit my invention thereto, since various modifications thereof will suggest themselves to those skilled in the 40 art without departing from the spirit of my invention, the scope of which is set forth in the annexed claims.

What I claim as new and desire to secure by Letters Patent of the United States is:

15 1. A flatiron comprising an ironing body provided in its side with a groove-like recess having a lower wall terminating in the surface of said side so as to leave a comparatively thin unbroken portion of said side between 20 said recess and the pressing surface of said iron whereby that portion of said pressing surface beneath said recess can be projected under a button or the like so as to iron the fabric under and about said button.

25 2. An electric flatiron comprising an ironing body having substantially vertical sides, said ironing body being provided in one of said sides with a recess having a lower wall terminating in the surface of said side so as to leave a comparatively thin unbroken portion 30 of said side between said recess and the pressing surface of said iron.

3. A flatiron comprising an ironing body having substantially vertical sides converging to a point at one end thereof, said ironing

body being provided with a recess in one of said converging sides adjacent the pressing surface of said iron, said recess having a lower wall terminating in the surface of said side so as to leave a comparatively thin unbroken portion of said side between said recess and said pressing surface.

4. A flatiron comprising an ironing body provided with a recess in its side for receiving a button or the like in the ironing operation so that the fabric under and about said button may be pressed, said recess having tapered end portions terminating in the surface of said side to facilitate the movement of the button into and from the recess.

5. A flatiron comprising an ironing body provided in its side with a recess having a lower wall inclined downwardly toward the surface of said side so as to leave but a comparatively thin portion of said side between said recess and the pressing surface of the iron whereby that portion of said pressing surface beneath said recess may be projected under a button or the like so as to iron the fabric thereunder, said recess also having tapered end portions terminating in the surface of said side to facilitate the movement of the button into and from the recess.

In witness whereof, I have hereunto set my hand, this 8th day of March, 1929.

EDWIN A. PETERSON.
